WINDING SPOOL AND GUIDE SUPPORT
THEREFOROtte W. Schlums, Whitinsville, Mass., assignor to
Whitin Machine Works, Whitinsville, Mass., a
corporation of Massachusetts

Application March 18, 1939, Serial No. 262,687

2 Claims. (Cl. 242—130)

This invention relates to spools on which thread is wound for textile purposes, and to guide supports therefor. Particularly, the invention relates to spools designed to receive silk, rayon or other delicate or easily soiled materials.

It is the general object of my invention to provide an improved spool and guide support, so designed that the spool may be readily removed from its supports and that the spool sleeve may be readily removed from the spool frame, all without manual contact with the thread wound on the sleeve.

A further object is to provide a guide support having improved means to prevent axial lost motion of the spool during a winding operation.

My invention further relates to arrangements and combinations of parts which will be hereinafter described and more particularly pointed out in the appended claims.

A preferred form of the invention is shown in the drawings, in which

Fig. 1 is a sectional end elevation of parts of a winding machine embodying my improvements;

Fig. 2 is a partial front view, looking in the direction of the arrow 2 in Fig. 1;

Fig. 3 is a side elevation, partly in section, showing a spool frame and spool sleeve partly separated;

Fig. 4 is a sectional side elevation of my improved spool;

Fig. 5 is a front view showing the manner of removing the spool from its guide supports;

Fig. 6 is a front view showing the manner of removing the spool frame from a spool sleeve having thread wound thereon; and

Figs. 7 and 8 are detail sectional views, taken along the lines 7—7 and 8—8 in Fig. 1 respectively.

Referring to Fig. 1, I have shown portions of a winding machine including a rail 10 supporting brackets 11 which provide spaced bearings for a winding shaft 12 which drives a plurality of axially-spaced winding rolls 13. The brackets 11 also uphold a cross bar 15, to which guide supports 16 for the winding spools are secured by clamping bolts 17.

Each guide support comprises a fixed frame member 20 having a substantially vertical guide groove 21 in one face thereof and a rectangular recess 22 in the opposite face. A block 24 is loosely mounted in the recess 22 but is secured from outward displacement by headed studs 25 fixed in the frame member 20.

Coil springs 26 are interposed between the block 24 and the member 20 and hold the block

in place and guide the block 24 in the recess 22. The frame member 20 is secured to the rail 10 by a suitable fastener 27. A slot 28 is provided in the frame member 20 to receive the ends of the coil springs 26.

Fig. 2 shows the spool 29 supported on the shaft 30.

Fig. 189 shows the frame member 20 and block 24.

Fig. 190 shows the frame member

- the recessed spool heads and lifting the spool S and spool shaft 30 out of the guide grooves 21 and 29. As this movement is approaching completion, the ends of the shaft 30 engage guard plates 55 (Fig. 1) on the upper ends of the supports 16, so that further movement must be forward as well as upward and the filled spool is thus kept clear of contact with adjacent parts of the machine.
- 10 After the spool has been thus removed, the operator grasps the ends of the levers 42 as indicated in Fig. 6 and presses them inward, whereupon the sleeve V and the thread T wound thereon may be deposited on a supporting surface and the spool frame F may be freely removed upward, all without contact with the thread T. This is extremely desirable when handling silk or rayon or similar materials in which the appearance is altered by the slightest contact therewith.
- 15 It will be understood that the number of spool frames F need be sufficient only to fill the winding machine, while spool sleeves V only need be provided for any required number of thread packages.
- 20 Claims to the novel guide support disclosed in this specification are not presented herewith but form the subject matter of a divisional application Serial No. 338,483, filed by me June 3, 1940.
- 25 Having thus described my invention and the

advantages thereof, I do not wish to be limited to the details herein disclosed, otherwise than as set forth in the claims, but what I claim is:

1. In a winding machine, a spool comprising a spool frame having inwardly recessed heads, a cylindrical yarn-supporting sleeve mounted on said frame, a pair of levers each pivoted at one end in one of said heads, the free ends of said levers extending into openings in the other head for manual release, springs to force said levers apart, and spurs on said levers engaging the inner surface of a sleeve mounted on said frame and preventing axial and angular displacement thereof on said spool frame.
- 10 2. In a winding machine, a spool comprising a spool frame having longitudinally spaced heads, axially extending bars connecting said heads and maintaining them in fixed spaced relation, a pair of diametrically opposed levers pivoted in one of said heads and freely movable radially in slots 20 in the other head, spring means to move said levers yieldingly outward and a cylindrical yarn-supporting sleeve axially slidable on said heads and connecting bars, said levers having sleeve-engaging and driving elements mounted thereon 25 and certain of said bars having transverse openings through which said elements are projected outward by said spring means to engage said sleeve.

OTTO W. SCHLUMS. 30
